The ornamental design for a loading unit for x-ray film
cassetts, as shown and described.

DESCRIPTION

FIG. 1 is a front elevational view of a loading unit for
x-ray film cassettes showing my new design;
FIG. 2 is a left side elevational view thereof;
FIG. 3 is a right side elevational view thereof;
FIG. 4 is a top plan view thereof;
FIG. 5 is a rear elevation view thereof; and,
FIG. 6 is a top, front, left side perspective view thereof.
The bottom of the loading unit is plain and unornamented.

FIG. 1

FIG. 2
